UNITED STATES PATENT OFFICE.

DAVID BAIRD MACDONALD, OF LEICESTER, ENGLAND.

APPARATUS FOR MAKING STIFFENERS FOR BOOTS AND SHOES.

Application filed June 8, 1926, Serial No. 114,434, and in Great Britain June 18, 1925.

This invention concerns apparatus for making boot and shoe stiffeners of the kind composed of a number of layers of material combined with a stiffening agent and is applicable 5 to those which require to be softened by heat prior to use and also to those which do not require such preliminary softening.

This invention chiefly relates to apparatus for making puffs or stiffeners for insertion 10 into the toe parts but it may be applied to stiffeners for insertion into other parts of boots and shoes.

The object of the invention is to produce 15 an improved stiffener of the kind referred to so constructed that one or more of its edges is or are reduced in thickness to obviate the formation of a ridge on the outside of the upper.

This is achieved by making the stiffener so 20 that the edge of one or more of the composite layers projects beyond the other or others and is not treated with the stiffening agent.

The invention includes apparatus for making the improved stiffeners as will be herein- 25 after described.

In describing the invention reference will be made to the accompanying drawings 30 wherein:

Figure 1 is a face view of one form of the 35 improved stiffener the view showing the composite layers partly separated.

Figure 2 is a similar view of another form 40 of the improved stiffener.

Figure 3 is a perspective view of a device 45 used for carrying out the method of manufacture herein to be described.

Figure 4 is a plan of the device shown in 50 Figure 3.

Figure 5 is a perspective view of an appa- 55 ratus which may be used in association with the said device.

Figure 6 is a front elevation, and

Figure 7 is a part sectional side elevation 60 of a power-actuated apparatus which may be employed according to the invention.

Figures 4 to 7 are drawn to a smaller scale 65 than Figures 1 to 3.

Referring to the drawings, the stiffeners 70 shown in Figures 1 and 2 comprises respec- 75 tively outer layers *a* and *b* and inner layers *c* and *d*. The layers *a* may consist of textile fabric such as white croydon and the layers *b* may consist of paper. The inner layers

preferably consist of reticulated textile ma- 55 terial but for some classes of work non-reticulated material such as swansdown may be used. One of the reticulated layers e. g. the layer *c* may be omitted. Or there may be more than two intermediate layers. Accord- 60 ing to the invention the intermediate layer *d* (or one at least of the intermediate layers where a number are used) is made larger than the remaining layers and the stiffening agent is applied thereto over a restricted area equivalent to the area of the outer layers so 65 that a marginal portion of the stiffener is left thin and pliant. Thus as represented in Figure 1 a stiffener having a rear edge *e* constituted by an untreated portion of the layer *d* may be produced, or, as shown in Figure 2, 70 a stiffener wherein the layer *d* projects all round to provide an untreated marginal portion *f* may be formed.

For making the improved stiffeners the de- 75 vice represented in Figures 3 and 4 may be used comprising a pair of plates 1 and 2, the plate 1 forming a guard being movable relatively to the other so that the layer to be treated with the stiffening agent may be placed and held between them. The guard 80 plate 1, has an opening 3 therein correspond- 85 ing in shape to the outer layers *a* and *b* of the stiffener, connected to a handle 4 by a hinge 5 the plate 2 being fixed to this handle. The fixed plate 2 may have its front and side edges 90 turned up to form a recess for the location of the layer *d* (or layers of more than one) to be treated when the hinged plate 1 is raised as represented by the dot and dash lines in Figure 3. Other means may be provided to po- 95 sition the layer on the plate 2. The opening 3 may be so located that when the layer is in position between the plates a margin or strip along the rear thereof, which subsequently constitutes the rear edge *e* of the stiffener 95 shown in Figure 1, is covered by the guard plate 1, leaving the remainder practically wholly exposed as represented in Figure 4 where the outline of the layer is shown by dotted lines. When the stiffening agent is to 100 be applied by means of rollers the plate 1 may be allowed to slightly overlap the layer at the front and thus prevent displacement of the layer at this point, so that in the finished stiffener the said layer will project slightly 105 at the front as represented in Figure 1. On

- the other hand the plate need not overlap as aforesaid so that the front edges of the various layers in the stiffener will correspond. For making the stiffener shown in Figure 2 the opening in the plate 1 is so disposed that the edge thereof overlaps the layer to the same extent all round so that the centre part is exposed to the stiffening agent thus leaving the untreated margin *f*.
- 10 When the layer is held between the plates of the device the stiffening agent may be applied to the part exposed by the opening by means of a brush, knife or equivalent after which the smaller covering layers *c* and *a* (or the layer *a* only if the layer *c* is omitted) may be applied and smoothed down, the guard plate serving as a guide for the added layer (or layers). The guard plate is then raised, the layer *d* with its attached layers 15 (or layer) is turned over and the operation 20 repeated to apply the other covering layer *b*. When the layer *d* is of reticulated material it may not be necessary to apply the stiffening agent to both sides, since when applied 25 to one side of the layer said agent may penetrate to the other side. When the inner layer is of non-reticulated material it will be necessary to treat both sides. In this case, or when instead of applying the stiffening agent with 30 a brush or equivalent the device containing the layer to be treated is passed between rollers or dipped in the stiffening agent the plate 2 may be formed with an opening similar to the opening 3 so that both sides of the layer 35 may be treated at once and the covering layers afterwards applied first on one side and then on the other. When both plates have an opening that in one may be smaller than that in the other, the covering layers 40 subsequently applied being of correspondingly different sizes so that a stiffener of graduated thickness may be produced. When the stiffener includes an inner reticulated layer *c* smaller than the layer *d* the latter may 45 have the former attached to it by a smaller quantity of the stiffening agent before insertion into the holder device and the combined layers may then be treated as one. If desired the holder may be fitted with a spring 6 50 which normally holds the two plates in contact i. e. closed and a thumb piece 7 may be provided on the plate 1 for raising the latter. The handle is, of course, used for manipulating the holder.
- 55 I may use a simpler form of device (not shown) consisting of a guard stencil plate cut from sheet material. The layer to be treated is laid upon a bench or table and the guard is placed on the layer to cover the portions not 60 requiring treatment leaving exposed the area which is to receive the stiffening medium which is then applied by a brush or other means after which the smaller covering layers for the stiffener are placed in position 65 upon the treated area and smoothed down,

the guard serving as a guide for the added layer. The guard is then removed, the treated layer with the attached smaller layers is turned over, the guard is applied to the face thus brought uppermost, and the operation 70 is repeated to treat this side of the article.

The stencil guard may be used by hand in the manner described, or it may be hinged or arranged on a bed, block, or table so that it can be raised for insertion and removal of 75 the stiffener layers. When the guard is hinged to a block or bed the latter may be shaped or provided with guides to enable the large layer or layers to be placed in correct position thereon so that when the guard is closed down upon the said layer or layers it will expose the desired area for reception of 80 the stiffening agent and protect by covering the marginal portion which is to remain untreated.

85 The holder device (Figures 3 and 4) may be used with an apparatus comprising a tank 8 (Figure 5) for the stiffening agent provided in front with a slot 9 through which the holder is pushed to carry the layer therein 90 into said agent and which is normally closed by a shutter 10 slidable between guides 11 and held in contact with a stop plate 12 by springs 13. The sliding shutter is connected for example by a pair of links 14, a lever 15 fulcrumed on the tank and a link 16 to a treadle or equivalent (not shown). When the treadle is depressed the shutter 10 is raised to uncover the slot so that the holder may be pushed into the tank and then withdrawn 100 thereby coating the exposed part of the layer with the stiffening agent. Guides 17 may be provided on the stop plate 12 to facilitate the insertion of the holder into the slot. A holder consisting of a slide operable by hand 105 or mechanically may be combined with the apparatus for carrying the layer into and out of the tank.

110 The apparatus shown in Figures 6 and 7 comprises a tank 18 of closed form having a filling orifice furnished with a cover, and having on the front thereof a slide comprising two plates 19 and 20 between which the layer or components which is or are to be treated or impregnated with the stiffening agent is or are held. The plates 19 or each plate is provided with a suitable opening the size and shape of which determines the area which is to receive the stiffening agent. The 115 slide is carried by a plate 21 mounted on a bracket 22 attached to another slide 23 movable in a guideway 24 fixed on one side of the tank and operated through the medium of a connecting rod 25, by a crank disc 26 fast on a shaft 27. This shaft is carried by a bearing 28 fixed on the bed plate 29 of the apparatus and is driven as hereinafter described. The slide is thus reciprocated to carry the layer or components into and out of the tank through a slot 30 suitably situated 120

for the purpose and having associated with it a displaceable shutter 31. The shutter is controlled by a laminated spring 32 arranged between abutments 33 and 34 on the tank and 5 shutter respectively. On the outward movement of the slide taking place the shutter scraped off surplus stiffening agent from the slide and coated layer or components. Inside the tank are rollers 35 and 36 between 10 which the slide travels and whereby the stiffening agent is forced into the exposed part or parts of the layer or components. One of the rollers e. g. 36 is mounted in spring-pressed bearings 37. When the slide is in 15 the outer position its forward end extends through the slot 30 and between the rollers, the shutter 31 pressing down upon the slide to prevent escape of the stiffening agent.

The lower plate 20 is made longer than 20 the top plate 19 (which is pivoted on the plate 20 by a hinge 38) and has a further plate 39 fixedly attached to it in front of the hinged plate. The hinged plate 19 can be raised by a thumb piece 40 for insertion and 25 removal of the layer or components when the slide is in the outer position shown and it may or may not be spring controlled. Instead of operation by hand the hinged plate 19 may be raised mechanically such as by an 30 abutment when the slide moves outwards alternatively, the slide may move right out of the tank and forcibly open the shutter upon its inward stroke, in which case the lower edge of the shutter or the forward edge of 35 the slide or both may be bevelled to facilitate the forcible lifting of the shutter when the slide moves inwards. Or the shutter may be opened and closed independently by suitable mechanical means. The shutter may be 40 furnished with rollers or small shoes to facilitate the opening and closing movement and may move between guides 41.

The rollers 35 and 36 are driven by gear 45 wheels and shafts actuated by an eccentric or equivalent in timed relation with the slide the latter operating with a reciprocating motion while the rollers rotate first in one direction and then in the opposite direction according to the movement of the slide.

50 Conveniently the movements of the parts are derived from a main shaft 42 rotatable in bearings 43 on the tank and fitted with driving means which include a single revolution clutch operable by a treadle or other 55 member in a manner well known. The crank-shaft 27 is driven from the main shaft 42 by chain gears 44, 45 and 46. An eccentric 47 on said shaft 42 engages rollers 48 on and thereby oscillates a frame 49 pivoted at 49^a 60 on the tank. A chain 50 attached at one end to one point on the frame 49 passes over a sprocket wheel 51 on a shaft 52 mounted in bearings 53 on the tank, and has its opposite end attached to the frame at another point 65 so that oscillation of the frame turns shaft 52

first in one direction and then in the other. A vertical shaft 54 driven by means of bevel gears 55, 56 from shaft 52 passes down inside the tank drives the roller 35 by bevel gears 57, 58. The shaft 54 and gears 57, 58 are 70 enclosed within a suitable housing 59 in the tank to prevent access of the stiffening agent thereto. When the slide normally extends between the rollers as hereinbefore described, the lower roller is driven frictionally by the 75 slide. When the slide is arranged to move right out of the tank, the lower roller is spring pressed into contact with the upper one and is thereby driven.

The method of making the stiffeners by 80 use of the apparatus just described may be the same as that previously described herein in the slide serving the same purpose as the hand manipulated device described with reference to Figures 3 and 4.

When the bottom plate 20 of the slide is made without an opening the reticulated inner layer or components of the stiffener and one of the outer layers may be placed in the slide in company, said outer layer being 90 placed under the other or others, so that when passed between the rollers 35 and 36 the reticulated layer or components will be impregnated with the stiffening agent and the various layers united simultaneously. Then 95 following the outward movement of the slide the other outer layer may be applied to the treated layers. In this manner it is possible by using a top plate 20 of suitable form and suitably positioning the component layers in the slide to produce a stiffener wherein the front edges of the various layers approximately correspond, as represented in Figure 1, while having an untreated marginal portion all round.

One or each plate of the slide may be 100 removable and interchangeable with others having different openings for making different stiffeners and the lower plate may have 105 marks, guides or other means to facilitate the correct positioning of the layer or components thereon.

The tanks shown in Figures 5, 6 and 7, may be jacketed for heating by steam or hot water.

Quick drying stiffeners of the kind herein described may be produced by preliminary treatment of one or more of the composite layers by applying the stiffening agent thereto as hereinbefore described, but over a 110 smaller area than that to be covered by the other layer or layers, then allowing the treated layer or layers to dry or partly dry, and subsequently treating the same over the larger area and applying the other layer or layers thereto.

For carrying out this method guards, holders or slides or interchangeable plates having correspondingly different openings therein may be provided.

115 Stiffeners produced as just described dry 130

more quickly than those having their treated layers impregnated at one operation, and as a result when inserted into boots and shoes enable lasts to be slipped sooner thereby expediting manufacture.

A stiffener with a thin flexible edge such as herein described is an improvement upon those at present used especially in the form of a toe puff since the rear edge of such articles 10 when thick is liable to form a ridge across the vamp or toe after lasting and particularly in turn-shoe work and work having thin upper material. By the method herein described the rear edge can be made thin to obviate the objection referred to.

The invention concerns principally though not exclusively composite stiffeners of the cold type and wherein the stiffening agent used consists of celluloid or the like in solution in a solvent of volatile character.

What I claim then is:—

1. For use in making stiffeners of the kind herein referred to, a holder device of stencil form comprising a pair of plates to expose for treatment a restricted area of a stiffener layer when placed between them, said plates being hingedly connected whereby they may be separated to receive the layer and closed to hold same, a handle on one plate for manipulation of the device, and guiding means on one plate to determine the position of the layer to be treated.

2. For use in making stiffeners of the kind herein referred to, a holder device of stencil form comprising a pair of plates to expose for treatment a restricted area of a stiffener layer when placed between them, said plates being hingedly connected whereby they may be separated to receive the layer and closed to hold same, a handle on one plate for manipulation of the device a spring to normally hold the plates closed and a thumb piece on the movable plate for actuation thereof.

3. For use in making stiffeners of the kind herein referred to, apparatus comprising a tank for the stiffening agent, a holder device comprising guard plates between which the stiffener layer can be held and have a restricted area exposed for treatment said holder device being adapted for insertion into the tank through a slot therein to carry the layer into the stiffening agent, and a shutter to normally close the slot in the tank.

4. For use in making stiffeners of the kind herein referred to, apparatus comprising a tank for the stiffening agent, a device comprising guard plates to hold and expose a restricted area of a stiffener layer, said device being adapted for insertion into the tank through a slot therein to subject the exposed area of the layer to the stiffening agent, a shutter to normally close the slot in the tank, a treadle and connections for operating the shutter.

5. Apparatus for making stiffeners of the kind herein referred to, comprising, a tank to contain the stiffening agent a slot therein and a slide having guard plates between which a layer of stiffener material may be held, said slide being movable through the slot to carry the layer into and out of the tank.

6. Apparatus for making stiffeners of the kind herein referred to, comprising a tank 75 to contain the stiffening agent, a slot therein, a shutter covering said slot, and a slide having guard plates between which a layer of stiffener material may be held, said slide being movable through the slot to carry the 80 layer into and out of the tank, and the shutter acting as a scraper on the slide to remove surplus stiffening agent from the treated layer.

7. Apparatus for making stiffeners of the kind herein referred to, comprising, a tank to contain the stiffening agent, a slot therein, a slide having a pair of guard plates one or each of which has a shaped opening to expose a restricted area of a layer of stiffener material held between them, one of said plates being movably associated with the other whereby they may be opened for reception of the layer and closed to hold said layer in position, said slide being movable through 95 the slot so as to carry the layer into and out of the tank for treatment by the stiffening agent.

8. Apparatus for making stiffeners of the kind herein referred to, comprising a tank to 100 contain the stiffening agent, a slot therein, a slide equipped with guard plates for holding a layer of stiffener material and exposing a restricted area thereof, said slide being movable through the slot in the tank to carry 105 the layer into and out of the stiffening agent, and means to impart reciprocation to the slide.

9. Apparatus for making stiffeners of the kind herein referred to, comprising, a tank 110 to contain the stiffening agent, a slot therein, a slide equipped with guard plates for holding a layer of stiffener material and exposing a restricted area thereof, presser rollers in the tank, the said slide being movable through 115 the slot in the tank to carry the layer into the stiffening agent and between the rollers, and means to impart reciprocation to the slide.

10. Apparatus for making stiffeners of the kind herein referred to, comprising, a tank to 120 contain the stiffening agent, a slot therein, a slide equipped with guard plates for holding a layer of stiffener material and exposing a restricted area thereof, presser rollers in the tank, the said slide being movable through 125 the slot in the tank to carry the layer into the stiffening agent and between the rollers, means to impart reciprocation to the slide, and means to drive the presser rollers first in one direction and then in the other in timed 130

relation with the reciprocating movements of the slide.

11. Apparatus for making stiffeners of the kind herein referred to, comprising, a tank 5 to contain the stiffening agent, a slot therein, a slide equipped with guard plates for holding a layer of stiffener material and exposing a restricted area thereof, a spring controlled shutter covering the slot and acting 10 on the slide, presser rollers in the tank, the said slide being movable through the slot in the tank to carry the layer into the stiffening agent and between the rollers, means to impart reciprocation to the slide, and means to

drive the presser rollers in timed relation to 15 the reciprocation of the slide.

12. Apparatus for making stiffeners of the kind herein referred to, comprising a stencil guard plate hinged to a block, bed or table the latter being shaped or provided with 20 guides to determine the position of a stiffener layer thereon, said stencil plate being adapted when closed down upon the layer to hold same and expose a restricted area thereof for reception of the stiffening agent, sub- 25 stantially as described.

In testimony whereof I affix my signature.

DAVID BAIRD MACDONALD.
